Carry S. Graye

ATTORNEY.

UNITED STATES PATENT OFFICE.

FRANK, CONLY, OF INDIANAPOLIS, INDIANA.

LOCK.

Application filed December 28, 1926. Serial No. 157,582.

This invention relates to locks, such as are primarily used for doors or the like and of the mortise type, and one feature of the invention is the provision of means for operating the locking bolt of the lock independently of the ordinary key, whereby the bolt may be released in the event of a lost key, and without removing any parts of the lock from the door.

10 A further feature of the invention is in so arranging the bolt releasing mechanism that it may be operated from either side of the door.

15 A further feature of the invention is in so arranging the bolt operating mechanism that it will normally be excluded from view, although permanently attached with the lock.

20 A further feature of the invention is in so constructing the bolt operating mechanism that it may be attached to an old lock or furnished as a built-in part of a new lock.

Other objects and advantages will be hereinafter more fully set forth and pointed out in the accompanying specification.

25 In the accompanying drawing which is made a part of this application—

Figure 1 is a side elevation of a portion of a door with the lock mechanism attached thereto.

30 Figure 2 is a vertical transverse sectional view through the door and lock.

Figure 3 is a side elevation of the lock removed from the door with parts of the casing broken away.

35 Figure 4 is an elevation of one face of the lock.

Figure 5 is a perspective view of the locking bolt and operating mechanism therefor.

Figure 6 is a perspective view of the locking bolt operating means, and,

40 Figure 7 is an elevation of an operating means for the bolt operating mechanism.

Referring to the drawing, 1 indicates the door, which may be of any preferred construction, 2 the lock therefor and 3 indicates the locking bolt used for securing the door in closed position.

It frequently occurs that the regulation key for locking or unlocking the door becomes lost or misplaced, thus necessitating the employment of a locksmith or the defacing of the door or casing in order to release the locking bolt but, by employing this invention these objectionable features are entirely overcome.

In addition to the key way 4 in the bolt

3, an auxiliary way or notch 5 is formed in the bolt, with which cooperates a tongue 6, carried by a shaft 7, the tongue 6 moving the bolt to open or closed position, when the shaft 7 is rotated. The shaft 7 extends transversely through the lock 2 and has its ends projecting a distance beyond each face thereof and the projecting ends are preferably provided with notches 8. Cooperating 60 with the shaft 7 is a key 9, preferably in the form of a wing nut, said key having a pin 10 extending across its interior for engagement with the notches 8, so that when the key is rotated the shaft 7 will be rotated 65 and the bolt 3 moved to locked or unlocked position.

Although the device is used primarily for releasing the locking bolt, it may be used for locking the bolt, and when so used, means is 70 provided for closing the ordinary key slot in the lock casing, consisting of a plate 11, slidably mounted on one inner wall of the lock casing, said plate having a notch 12, with which engages a tongue 13, on the shaft 75 7, so that when the bolt 3 is operated, the plate 11 will be simultaneously operated. The plate 11 has a key socket 14, which moves to registration with the key socket 15 in the lock casing, when the bolt 3 is in unlocked 80 position and is moved out of registration therewith when the bolt is moved to locked position by the operation of the shaft 7. The plate 11 is not operated, however, when the ordinary key is used for moving the bolt 3 85 into or out of locking position. The moving of the plate 11 in one direction, as when the bolt 3 is moved to locked position by rotating the shaft 7, will move the key socket 90 14 out of registration with the key socket 15, hence it will be impossible to insert the ordinary key for releasing the bolt 3.

The ends of the shaft 7 enter cavities 16 in the faces of the door 1, and these cavities are so placed that they will be covered by the ordinary face plates 17, of the lock, thus excluding the bolt operating mechanism from view, but when it is desired or necessary to operate the locking bolt 3, otherwise than by the use of the ordinary key, the screws 18 100 are released from the face plate 17 and the lower end of the plate swung laterally until the cavities are exposed. The key 9 may then be utilized for operating the locking bolt 165 3 to move it into or out of locking position.

110 The key 9 may be introduced over the end of the shaft 7 and left in that position, as

the cavities 16 are of sufficient depth to accommodate the key without striking against the plates 17, or it may be removed and carried in the pocket, or placed in some convenient place. It will be understood of course, that any suitable instrument, other than the key 9, may be used for rotating the shaft 7.

This invention can be very cheaply manufactured and readily applied to use and entirely excluded from view, thus giving no indication to any one not acquainted with the structure of the lock, that the bolt could be unlocked without employing the ordinary door key.

What I claim is:

1. The combination with a lock including face plates and having a key operated locking bolt, of means independent of the key 20 adapted to move said bolt to locked or unlocked position, said independent locking means being positioned below said face plates for excluding said independent bolt operating means from view.

2. The combination with a lock including

face plates and a key operated locking bolt, of a shaft extending transversely through said lock, means on said shaft for engaging and operating said bolt when the shaft is rotated, and means for operating said shaft, 20 said shaft operating means being concealed from view by said face plates.

3. The combination with a lock including face plates and a locking bolt, of a shaft extending transversely through said lock, a 35 tongue on said shaft adapted to engage and operate said bolt, and means for operating said shaft, said shaft and operating means therefor being excluded from view by said face plates.

4. The combination with a lock having a key operated locking bolt therein, and an opening to receive said key, of means within the lock for operating said bolt, and means for covering said key opening when the bolt is moved by said means to locked position 45 for preventing the insertion of said key.

In testimony whereof I hereto affix my signature.

FRANK CONLY.
